(57) **CLAIM**

The ornamental design for a pen, as shown and described.

DESCRIPTION

FIG. 1 is an upper front right perspective view of a pen showing my new design;
 FIG. 2 is a left side elevation view thereof, with the right side elevation view being a mirror image of the left side elevation view;

FIG. 3 is a front elevation view thereof;

FIG. 4 is a rear elevation view thereof;

FIG. 5 is an enlarged top plan view thereof; and,

FIG. 6 is an enlarged bottom plan view thereof.

The broken lines around the inside surface in FIG. 5 are included for the purpose of illustrating a portion of the pen that forms no part of the claimed design.
